UNITED STATES PATENT OFFICE.

ARTHUR R. SIEGLER, OF DENVER, COLORADO.

INTERNAL-COMBUSTION ENGINE.

Application filed February 20, 1925. Serial No. 10,572.

This invention relates to the internal combustion engine described and illustrated in the applicant's co-pending application, Serial No. 3978, and since it is an improvement 5 on the previously shown structure, only sufficient has been illustrated to disclose the relation therewith.

The principal object of the invention is to provide means for removing fluid from 10 the upper portion of an internal combustion fluid engine cylinder so as to prevent waste of oil and the formation of carbon.

A further object of the invention is to provide means for preventing fluid from 15 entering the ports of a sleeve valve as employed in internal combustion engines of the type disclosed in the said copending application.

A still further object is to provide means 20 for collecting the fluid which customarily gathers in the port openings of an internal combustion fluid engine and returning this oil to the system.

Other objects and advantages reside in the 25 detail construction of the invention, which result in simplicity, economy, and efficiency, and which will become more apparent from the following description.

In the following detailed description of 30 the invention, reference is had to the accompanying drawing which forms a part hereof. Like numerals refer to like parts in all views of the drawing and throughout the description. In the drawing:

35 Figure 1 illustrates a side elevation of a cylinder of an internal combustion engine of the fluid type such as described in the said co-pending application. In this view, the cylinder wall is broken away to illustrate the interior construction.

40 Figure 2 is a detail view showing round ports in place of the rectangular ports of Figure 1.

The invention comprises a cylinder 10, 45 closed at its bottom as shown at 11, and provided with a cylinder head 12. The cylinder head carries an opening 13 through which fuel is admitted to the combustion chamber. In the cylinder illustrated, the 50 fuel is ignited by the compression temperature in the cylinder. In the cylinder 10, an internal reciprocating sleeve valve 14 is arranged. The sleeve valve 14 is reciprocated by means of an arm 15 and a connecting rod 16 operated from any convenient 55 source such as illustrated in the said co-

pending application. A piston 17 reciprocates within the sleeve valve 14.

The cylinder 10 is provided with an exhaust manifold 18, from which exhaust ports 19 open to the interior of the cylinder; with a compressed air manifold 32, from which air ports 21 communicate with the interior of the cylinder; with a fluid discharge manifold 22, from which discharge ports 23 communicate with the interior of the cylinder; and with a fluid intake manifold 24, from which intake ports 25 communicate with the interior of the cylinder. The sleeve valve 14 is provided with compressed air openings 26, arranged to register with the air ports 21, and with fluid discharge openings 27, arranged to register with the discharge ports 23. The exhaust ports 19 and intake ports 25 are opened and closed by the upper and lower edges of the sleeve valve 14, respectively. A fluid intake pipe 28 communicates with the fluid intake manifold 24 and a fluid discharge pipe 29 communicates with a fluid discharge manifold 22. A compressed air pipe 41 communicates with a compressed air manifold 21 and an exhaust pipe 18' communicates with the exhaust manifold 18.

55 As illustrated, the sleeve valve 14 is in the scavenging position. Compressed air is flowing from the pipe 41 through the compressed air manifold 20, the air ports 21, and the openings 26 into the cylinder. This compressed air is forcing the burned 60 gases through the exhaust ports 19, the exhaust manifold 18, and the exhaust pipe 18'. 65

During the next cycle of operation, the sleeve valve 14 will be moved to the top of the cylinder by the connecting rod 16, thus 70 closing the ports 19 and 21 and opening the ports 23 and 25. Fluid under pressure 75 from a fluid turbine (not shown) now enters the cylinder 10 from the pipe 28 through the intake manifold 24 and the intake ports 25. The fluid discharge pipe 29 is closed 80 by an external valve (not shown) such as illustrated in the applicant's said co-pending application. The fluid forces the piston 17 upward in the cylinder compressing the air 85 at the upper end thereof.

90 When the compression has reached a predetermined point, fuel is admitted through the opening 13 and exploded. The pressure 95 of the explosion forces the piston 17 downward, driving the fluid through the discharge opening 27, discharge ports 23, dis- 100

charge manifold 22, discharge pipe 29 and the throttle valve (not shown) mentioned above, which is now open, to the said fluid turbine or any other suitable power device.

5 I have found that fluid escaping around the piston 17 will enter the openings in the sleeve valve 14 and the ports in the cylinder. This fluid will be blown into the cylinder by the incoming compressed air and will 10 be either carried away by the exhaust or burned during the combustion. I eliminate this loss of fluid by providing angularly placed channels 30 in the sleeve valve wall above the ports 26 and in the cylinder wall 15 above the ports 19. These channels act to conduct fluid flowing down the walls, to the side of the ports so that it will flow down alongside of, not into the port openings.

Any fluid which may collect in the openings 26 of the sleeve valve, is removed by providing relatively narrow slots 31 in the cylinder wall immediately above each of the compressed air ports 21. These slots communicate with an external jacket 32 which surrounds the cylinder 10 and from which the fluid is drained back to the system by means of a drain pipe 33. There is no communication between the exhaust manifold 18 and the jacket 32.

20 The slots 31 operate as follows: As the sleeve valve descends after the explosion cycle, each of the openings 26 must pass over one of the slots 31. At this time there is sufficient compression in the cylinder, as 25 a result of the explosion, to drive any fluid pocketed in the openings 26 through the slots 31 into the jacket 32, so that, when the openings 26 register with the compressed air ports 21 they will be practically free from 30 fluid.

Any fluid flowing down the wall of the sleeve valve 14 will collect in a peripheral groove 34 cut in the piston 17 and as the piston moves upward, during the compression cycle, the collected fluid in the groove 45 will flow into the openings 26 from where it is removed to the slots 31, as before described. The groove 34 is curved in cross section, as illustrated on the drawing. This 50 curve is so designed that the contained fluid will be thrown against the cylinder wall as the piston moves downward. The piston 17 is driven downward with considerable velocity. The inertia of the fluid contained in 55 the slot causes it to follow the curve of the slot and be dashed against the inner wall of the sleeve valve 14.

Should the contact between the sleeve 60 valve 14 and the cylinder 10 or the piston 17 and the sleeve valve 14 be relatively loose, fluid will spurt upward between the contacting surfaces. To prevent this upward spouting fluid from collecting on the cylinder head 12, I form a groove 35 in the cylinder 65 head in which the upward spouting fluid

is confined and directed downward along the walls of the cylinder and sleeve valve.

When round ports and openings are employed in the cylinder walls and sleeve valve, such as illustrated at 40, Fig. 2, I 70 form a groove 36 completely surrounding the port which serves to deflect fluid from the port opening. Should the engine be required to operate at times in other than a vertical position, any fluid which may be at 75 that time above the piston 17 will flow toward the cylinder head 12, and collect in the groove 35 from whence it will flow downward along the cylinder walls when the engine regains its normal position. A V-shaped groove 37 is formed in the sleeve valve below each series of openings 26 to deflect fluid from the openings when the cylinder is in the inverted position. With 80 the round ports, the groove 36 will serve to 85 deflect fluid from the port openings in any position of the cylinder.

Fluid flowing down the cylinder walls is deflected to the interior of the sleeve valve by a beveled edge 38 formed on the upper 90 extremity of the sleeve valve 14.

While a specific form of the improvement has been described and illustrated herein, it is desired to be understood that the same 95 may be varied, within the scope of the appended claims, without departing from the spirit of the invention.

Having thus described the invention, what I claim and desire secured by Letters Patent is:—

1. Means for preventing fluid from entering the ports of a combustion engine cylinder comprising angularly placed channels formed in the walls of said cylinder so as to direct the flow of said fluid away from 105 said ports.

2. Means for removing fluid collected by the ports of a sleeve valve in an internal combustion engine comprising, slots formed in said cylinder and arranged to register 110 with the ports of said sleeve valve so as to remove collected fluid therefrom.

3. In an internal combustion engine comprising a cylinder and a piston arranged to reciprocate within said cylinder; means for collecting fluid against the wall of said cylinder comprising, a peripheral groove formed near the upper extremity of said piston.

4. In an internal combustion engine, means for preventing the collection of fluid on the head of said cylinder, said means comprising a circular groove formed in the head of said cylinder adjacent the walls thereof.

5. Means for removing fluid collected by the ports of a sleeve valve in an internal combustion engine comprising, slots formed in said cylinder and arranged to register with the ports of said sleeve valve so as 130

to remove collected fluid therefrom, and a jacket surrounding said cylinder and arranged to receive fluid from said slots.

6. An internal combustion engine comprising a cylinder, a sleeve valve arranged to reciprocate in said cylinder, and a piston operating within said sleeve valve, said sleeve valve having a beveled upper extremity so as to direct fluid from the walls

of said cylinder to the interior of said sleeve 10 valve.

7. Means for preventing fluid from entering the ports of a combustion engine cylinder comprising annular grooves formed in the walls of said cylinder and surrounding said ports. 15

In testimony whereof, I affix my signature.

ARTHUR R. SIEGLER.
